(57) **CLAIM**

The ornamental design for a scanner, as shown and described.

DESCRIPTION

FIG. 1 is a front perspective view of a scanner showing our new design;

FIG. 2 is a front view thereof;

FIG. 3 is a rear view thereof;

FIG. 4 is a left side view thereof, a right side view is a mirror image of the left side view;

FIG. 5 is a top plan view thereof;

FIG. 6 is a bottom plan view thereof;

FIG. 7 is a perspective view showing the scanner with the catch tray closed; and,

FIG. 8 is a perspective view showing the scanner with the guides extended from the shoot and catch tray.

(Continued)

The portions depicted in broken line illustrate parts of the scanner that form no part of the claimed design.

1 Claim, 5 Drawing Sheets
